UNITED STATES PATENT OFFICE.

BENJAMAN J. BUELL, OF READING, PENNSYLVANIA.

CAR-WHEEL SKID-SHOE.

1,343,614.

Specification of Letters Patent. Patented June 15, 1920.

Application filed September 23, 1919. Serial No. 325,706.

To all whom it may concern:

Be it known that I, BENJAMAN J. BUELL, a citizen of the United States, residing at Reading, in the county of Berks and State 5 of Pennsylvania, have invented certain new and useful Improvements in Car-Wheel Skid-Shoes, of which the following is a specification.

This invention relates to improvements in 10 car wheel skid shoes and more particularly to that class of devices adapted to slide on the rail and be positioned between the rail and wheel to lift and maintain the wheel off of the track when the same has been 15 damaged and it is necessary to get the car back to the shop for repairs without the removing or turning of the car wheel.

The principal object of the invention is 20 to provide a wheel skid capable of being used in both a forward and backward direction, thus making the same substantially reversible and it is immaterial whether the car is being drawn ahead or backed during 25 its travel to the yard. After the device has once been applied to the wheel the same is substantially locked thereon and the car can be run in either direction, as will be hereinafter more fully described.

Another feature of applicant's invention 30 is the manner of locking the car wheel in place on the device so that the wheel cannot be displaced therefrom when the car is moved in a forward direction or backward direction, as distinguished from the older 35 type of skids capable of use only in one direction without shifting or completely turning the skid around.

Another object of the invention is to provide 40 a self lubricating wheel skid in order that the same might ride the rail with the least amount of friction and wear and thereby greatly increasing the efficiency of the device, particular reference being had to the lubricating of the forward or rounded 45 end of the shoe, so that when in use and weight is brought against the forward chock the lubrication of this forward portion will prevent the binding or sticking of the shoe in case the same should be tilted 50 forward slightly during its initial movement.

Briefly stated, applicant's device 55 comprises substantially a hollow or recessed casting in the form of a wheel skid shoe having a bearing upon the track through-

out its entire length, and adapted to be inserted under the car wheel between the rail and the wheel, to support the wheel, said device being provided with means for locking the car wheel against forward and backward movement with respect to the skid, 60 said skid also containing a lubricant, and means for supplying said lubricant to its rail engaging surface to reduce the frictional contact with the rail and minimize 65 the wear on the device when in operation.

With the foregoing and other objects in view, the invention resides in the combination and arrangement of parts and the details of construction hereinafter set forth 70 and claimed, it being understood that changes in the precise embodiment of invention, herein disclosed, can be made within the scope of the claims without departing from the spirit of the invention. 75

Referring to the drawings in which like numerals indicate like parts throughout the several views,

Figure 1 is a perspective view showing the device as applied to a car wheel. 80

Fig. 2 is a bottom plan view showing the openings connecting with the lubricant containing recesses.

Fig. 3 is a longitudinal sectional view 85 showing the oil and grease containing recesses, and movable chock adjusted in position, and Fig. 4 shows a modified construction of the grooved after portion of the device.

In the preferred form of applicant's de- 90 vice or skid shoe, 1 represents the main body portion of elongated formation having a rail engaged surface 2 comprising the bottom, and a top 3 upon which is supported the car wheel when the skid is in 95 operative position.

At one end of the main body portion, which for the purpose of description will be called the forward end, there is an upstanding or raised member comprising a chock 100 or stop 4, said chock having an inner curve 5 of a general contour corresponding to the outer periphery of a car wheel. The opposite face of the chock 4 is also curved as at 6, the lower portion of which, by a reverse 105 curve, rounding into a nose 7 slightly elevated in a plane above the straight portion of the bottom 2 and also slightly above the top of the rail when the skid is in position on the rail. 110

At the opposite or rear end of the elongated body portion 1 there is provided a reduced portion in the form of a bifurcated tongue 9 having an incline 10 upon which the car wheel rides when being elevated from the rail to position on the main body of the skid.

Adjoining the upper part of the incline 10 on the after end of the straight portion 10 of the top 3, there is provided a series of transverse notches or grooves 11 for the purpose as will be hereinafter more fully described. Positioned upon this after end there is an adjustable chock 12 having a forward incline face 13 and a bottom face provided with grooves 14 corresponding with the grooves 11 of the main body portion, the grooves 11 and 14 thus forming an interlocking engagement when the chock is in its final or adjusted position. To maintain the chock in its adjusted position and co-operating with the notches or grooves 11 and 14, there is a bolt or similar fastening 15 passing through the chock and the after 25 end of the main body portion of the skid shoe. Preferably, the nut 16 on the bolt is set up against the upper portion of the chock 12 and the head of said bolt underlies the grooved portion 11 of the after end 30 of the skid so that said nut may be readily manipulated, which construction is obvious.

To facilitate easy and ready adjustments of the chock 12 carrying the fastening 15, the rear or tapered end of the device is bifurcated, providing an elongated opening 16 running from the extreme rear end of the device up to and including the notched portion 11 as clearly shown in the drawings. Along the inner edges of the bifurcated 40 tongue 9, forming the opening 16, there are provided angular shoulders or rabbets 17. These rabbets are to accommodate the head of the fastening or bolt during the operation of sliding the adjustable chock in position 45 on the skid, and also act as a stop for the head of said bolt when setting up the nut after the chock has been placed in the desired position.

Extending downwardly from the inner 50 side of the device and about midway thereof is a dependent flange 8 which, when the skid is being drawn along the rail, maintains the device on the rail, acting in a manner similar to a flange on a car wheel, which will be 55 plain to one skilled in the art.

For the purpose of supplying a lubricant to the rail between the top of the rail and the rail engaging surface of the wheel skid, there are provided a series of cavities or 60 recesses 19 for containing oil or grease in any preferred form, each of said lubricant containing cavities having a feed opening 20 through which the oil or grease passes to the rail. In addition to the above-mentioned recesses or cavities and in order to

lubricate the forward or rounded portion of the skid shoe, the forward integral chock is made substantially hollow, forming in itself a lubricant containing cavity 21 which in my preferred embodiment of the invention contains oil waste but, of course, any other form of oil or grease may be used. Similar to the construction of the feed openings 20 said cavity 21 is provided with opening 22 which acts and performs the same 75 function as the openings 20. The lubricating of this forward end portion of the skid shoe is particularly desirable as it affords easy riding of the shoe over uneven rails and similar obstructions and also prevents 80 jamming or sticking of the shoe during the initial movement of said shoe when the device is in operation.

Fig. 4 illustrates another manner of forming the transverse grooves 11, wherein the 85 said grooves do not extend all the way to the edge of the skid, but leave a smooth portion 18 along each side thereof. Of course, if this construction is used, the co-operating grooves in the movable chock would also 90 have to be changed to conform thereto.

From the foregoing description the operation of the device is obvious. Placing the skid shoe on a track in front of a broken wheel the car is drawn forward and the 95 wheel drawn up the incline onto the straight portion of the device until it engages the forward stop. The adjustable chock is then placed in position on the skid with its grooved under face in engagement with the 100 grooved after end of the elongated body portion and the forward inclined face of the movable chock in engagement with the after side of the wheel tread. During this 105 adjustment the locking bolt is guided in the opening formed by the bifurcated tongue, the head of the bolt fitting in the angular grooves or rabbets along the inner edges of the bifurcated tongue as clearly shown in the drawing. After adjusting the movable 110 chock to the wheel it is only necessary to set up on the nut of the locking bolt and the device is ready for use.

What I claim is:

1. In a car wheel skid shoe, a main body 115 portion having on its inner lower edge a rail engaging flange, an integral raised portion at one end and an adjustable member or chock at the other end and co-operating grooves on the chock and main body portion for securing said chock in its adjusted position.

2. In a car wheel skid shoe a main body portion having on its inner lower edge a rail engaging flange, an integral raised portion at one end, a chock at the other end co-operating 120 grooves on the chock and main body portion for locking said chock to said main body portion, and means for maintaining said chock and main body portion in their interlocked position.

3. In a car wheel skid shoe, a main body portion, an integral raised portion at one end, an adjustable chock at the opposite end and coöperating means on said main body portion and adjustable chock for locking said chock in its adjustable position.

4. In a car wheel skid shoe, a main body portion provided with a series of recesses, a lubricant carried within said recesses, means 10 for feeding the lubricant to the rail from said recesses and means carried by said main body portion for securing the wheel thereon against both forward and backward movement.

15 5. In a car wheel skid shoe, an elongated main body portion, a substantially hollow integral raised portion at one end adapted to contain a lubricant, an adjustable chock at the opposite end, and means for feeding the 20 lubricant from said hollow end portion, to the rail.

6. In a car wheel skid shoe, a main body portion provided with a series of recesses, a substantially hollow integral raised end portion, said recesses and hollow end portion 25 adapted to contain a lubricant, and openings through the rail engaging surface of the de-

vice to said recesses for feeding the lubricant to the rail during the operation of the device.

7. In a car wheel skid shoe, a main body portion adapted to be positioned between the rail and the car wheel, and means for securing said wheel on the device independently of the car structure, said main body portion being provided with a series of recesses for supplying a lubricant between the rail engaging surface of the device and the rail.

8. In a car wheel skid shoe adapted to be positioned between the rail and the car wheel, and main body portion provided with a series of recesses, and substantially hollow integral raised end portion, said recesses and hollow end portion adapted to contain a lubricant, openings through the rail engaging surface of the device to said recesses for feeding the lubricant to the rail during the operation of the device, and means for locking the car wheel on said main body portion 45 against both forward and backward movement.

In testimony whereof I affix my signature.

BENJAMAN J. BUELL.
